UNITED STATES PATENT OFFICE.

WILLIAM W. LARGENT AND CHARLES A. STILES, OF TYRONE, PENNSYLVANIA.

SOCKET MEMBER.

Application filed April 6, 1926. Serial No. 100,119.

This invention relates to new and useful improvements in socket wrenches and has for its primary object to provide means whereby a nut that has been threaded off of the bolt may be projected from the socket for overcoming the fishing of the same therefrom which is usually necessary when a nut is jammed therein.

An additional object of the invention is to provide means for locking sockets of various sizes and shapes upon the ends of the wrench handle for preventing the disengagement of the same therefrom during the application of the socket upon a nut.

Other objects will become apparent as the nature of the invention is better understood, the same comprising the novel form, combination, and arrangement of parts herein-after more fully described, shown in the accompanying drawings and claimed.

In the drawing wherein like reference characters indicate corresponding parts throughout the various views:

Figure 1 is a view in side elevation partly in cross section of a socket wrench constructed in accordance with the present invention.

Figure 2 is a transverse section of the socketed end of the wrench taken substantially upon the line 2-2 of Figure 1, and

Figure 3 is a fragmentary section through the wrench at the forward end thereof for more clearly disclosing the means for ejecting the nut from the socket after removal from a bolt and for locking the socket member upon the end of the wrench handle.

Now having particular reference to the drawing, our novel socket wrench constitutes the provision of a handle bar 5 of any desirable length that is circular in cross section that is provided at one end with a head 6 through which extends an opening for receiving a turning rod 7, the opposite end of said handle being squared as at 8, for engagement within a similar shaped opening 9 in the end of a nut receiving socket member 10 any number of which may be employed in conjunction with the wrench in order to permit the use of the same upon nuts of various sizes and shapes.

Slidable within a longitudinal bore 11 at the forward end of the handle 5 is a pin 12 that is provided at the end of the handle with a circular disc 13 that normally rests upon the end of the handle as clearly shown in Figure 3. The inner end of said pin 12

is provided with a right angularly extending bent portion 14 slidable within a slot 15 formed in the handle at the lower end of said bore and to which is rigidly attached a sleeve 16 that is slidable upon the handle to facilitate the movement of the pin 12 in opposite directions within the bore 11. For maintaining said sleeve against free sliding movement there is provided a strip of spring metal 17 that is anchored at its opposite ends within said handle, said strip extending between the sleeve and handle, Figure 1. Said spring frictionally engaging the inner surface of the sleeve in an obvious manner.

The four sides of the opening in the closed end of the socket member 10 are formed with concave notches 18 for receiving the rounded projecting end of a short pin 19 that is loosely arranged within an opening in the handle 5 at the squared end thereof that communicates at the inner end with the bore 11 within which is movable said pin 12. The pin 12 is formed at its forward end and at its side adjacent said pin 19 with an elongated notch 20 in order that when the pin 12 is entirely within the bore of the handle said pin 19 may be forced rearwardly to permit the disengagement of the socket member 10 from the handle. However, after a nut has been removed from a bolt and it is desired to project the same from the socket member, the sleeve 16 is moved forwardly at which time the disc 13 will engage the nut for discharging the same.

During the outward movement of the pin 12 the notch 20 thereof will extend beyond the pin 19 and prevent the inward movement thereof which will serve to rigidly lock the socket upon the handle for preventing the disengagement of the same while manipulating the nut discharging means.

A pin or lug 21 is arranged upon the end of the handle beneath the locking pin 19 for limiting the inward movement of the socket member upon the handle while loosely arranged upon the handle is a hand grasping sleeve 22 to permit of the free rotation of the tool while the same is being held and steadied by one hand of the workman.

It will thus be seen that we have provided a highly novel, simple, and efficient form of socket wrench that is well adapted for all the purposes heretofore designed, even though we have herein shown and described the wrench consisting of certain detail structural elements it is nevertheless to be under-

stood that minor changes may be made therein without effecting the spirit and scope of the appended claims.

Having thus described the invention, what we claim as new and desire to secure by Letters Patent is:—

1. In a wrench of the character described, a handle, a nut receiving socket for arrangement upon one end of the handle, means associated with the handle for engagement in the socket whereby the nut may be projected therefrom and automatic means for locking the socket upon the handle as the nut is being projected.
2. In a wrench of the character described, a handle, a nut receiving socket for detachable arrangement upon one end of the handle, means whereby the nut may be projected from the socket after detachment from the bolt and automatically operable means for locking the socket upon the handle as the nut is being projected therefrom.
3. In a wrench of the character described, a handle having a bore, a nut receiving
- socket for detachable engagement upon one end of the handle, a pin slideable within the bore in the socket attaching end of the handle and projecting at one end within said socket, means for forcing the pin through the socket for projecting the detached nut therefrom and automatic means for locking the socket member to the handle as said pin is being moved to nut projecting position.
4. In a wrench of the character described, a handle having a bore, a socket adapted for detachable engagement upon one end of the handle, a pin slideable within the bore in the socket attaching end of the handle and engaging at its forward end with said socket, means for projecting the pin through the socket for discharging the nut therefrom, and means operable by the pin when moved to nut projecting position for locking the socket upon the handle.

In testimony whereof we affix our signatures.

WILLIAM W. LARGENT.
CHARLES A. STILES.
